OVERVOLTAGE PROTECTOR

Robert L. Brown, Teaneck, N. J., assignor to Bendix Aviation Corporation, Teterboro, N. J., a corporation of Delaware

Original application October 15, 1947, Serial No. 779,992. Divided and this application October 5, 1949, Serial No. 119,725

3 Claims. (Cl. 322—28)

1

This application is a division of application Serial No. 779,992, filed October 15, 1947, and relates to overvoltage protection for an electrical generator and more particularly to improvements in the system and protector of the type shown in the copending application for U. S. Patent Serial No. 701,322, filed October 4, 1946, by Robert Lowell Brown, now U. S. Patent No. 2,522,601.

An object of the invention is to provide overvoltage protection which does not respond to sudden surges of short duration of overvoltage.

It is desirable in the event of an overvoltage on one generator of a parallel arrangement that the other protectors do not trip due to surges caused by the finite time of operation of the faulted protector, reverse current relays, regulators and line switches. While the regulators of the normally functioning generators will automatically tend to keep the non-faulted protectors from tripping after a short, an object of the invention is to provide means for effecting an immediately acting time delay (of short duration) to keep the protectors from tripping before the regulators can take over.

Another object of the invention is to provide an immediately acting time delay (of short duration) for the protector which is introduced by the use of short circuiting slugs (rings) of copper arranged concentric with the coil on the electromagnet. Thus with the time delay in the protector plus the correcting action of the regulator the non-faulted protector will not trip when a parallel system is disturbed by an overvoltage generator.

The above and other objects and features of the invention will appear more fully hereinafter from a consideration of the following description taken in connection with the accompanying drawings wherein one embodiment of the invention is illustrated by way of example.

In the drawings:

Figure 1 is a perspective view of the overvoltage protector showing the vacuumtight casing and manually operable reset bellows;

Figure 2 is a perspective view of the overvoltage protector showing the vacuumtight casing and manually operable reset bellows;

Figure 3 is an enlarged sectional view of the overvoltage protector with the latch shown in the released position.

Figure 4 is a fragmentary end view of the switch mechanism showing the armature and latch mechanism.

Figure 5 is an end view of Figure 3 taken along

the lines 5—5 and looking in the direction of the arrows.

Figure 6 is a diagrammatic view showing the overvoltage protector connected into a generator system.

Referring to the drawings of Figures 2—3 there is shown the overvoltage protector which includes an electromagnetic coil 10 supported by a bracket 11 which with a second bracket 12 are fastened to a supporting plate 13 and base member or panel 13A by bolts 14.

The electromagnetic coil 10 has an armature 15 pivoted on an edge 16 formed at the outer end of the bracket 11. A third bracket arm 17 is fastened to the bracket 11 by a bolt 18 which also fastens thereto a member 19. A spring 20 is connected at the free end of the member 19, while the opposite end of the spring 20 is connected to the upper end of the armature 15 so as to bias the armature 15 about the edge 16 in a clockwise direction.

Positioned adjacent the armature 15 is a latch member 21 pivotally supported at one end by a spring arm 22. The latch member 21 is arranged to engage a shoulder portion 23 of a reset plunger or push rod 24. The push rod 24 is slidably mounted in portions 25 and 26 of the bracket 12.

At the upper end of the push rod 24 there is provided a head portion 27. Positioned between the head portion 27 and the bracket portion 25 is a coil spring 28 which biases the push rod 24 upwardly. A stop 29 is provided at the lower end of the push rod 24 to engage the bracket portion 26 so as to thereby limit the upward movement of the push rod under the biasing force of the spring 28. A cup-shaped depression 30 is formed in the supporting plate 13 for receiving the lower end of the push rod 24 when in the depressed position.

The supporting plate 13 has an upstanding flanged portion 31 extending about the outer edge thereof to which there is sealingly connected the lower edge of casing 32 which encloses the protector mechanism.

The casing 32 has an opening 33 formed therein through which projects the head portion 27 of the push rod 24. A bellows 34 surrounds the head portion 27 and the opening 33 and is sealingly connected to the casing 32. The upper end of the head portion 27 is operably connected interiorly to the bellows 34 so that depression of the bellows 34 effects downward adjustment of the push rod 24 so as to effect engagement of the shoulder 23 by the latch member 21.

The armature 15 carries a head stud 35, the

shank of which extends loosely through an aperture in the latch member 21, thus forming a loose or lost motion connection between the armature 15 and latch member 21. With this arrangement it will be seen that upon energization of the electromagnet 10 the voltage at which the armature 15 starts to move is determined by the spring 20. After the armature 15 has approached quite close to the pole face of the electromagnet 10 (at which position the pull of the electromagnet 10 is much greater) the head of the stud 35 engages the latch member 21 and pulls it off the step 23 of the push rod 24, thus permitting the rod 24 to move upward under the biasing force of the spring 28, to operate a plurality of switch contacts, as will be explained.

Mounted on the bracket arm 17 by bolts 36 is a switch assembly comprising insulating spacers 37, 38, 39, 40, 41, 42 and 43 and contact carrying spring arms 44, 45, 46 and 47 suitably insulated by the spacers.

As shown in Figure 5 there is further mounted on the bracket arm 17 by bolts 36A a second switch assembly comprising insulating spacers 37A, 38A, 39A, 40A, 41A, 42A and 43A and contact carrying spring arms 44A, 45A, 46A and 47A insulated by the spacers.

Also secured to the bracket arm 17 by the bolts 36 and 36A are insulation strips 50 and 51. Contact carrying spring arms 52 and 53 are fastened respectively to the insulation strips 50 and 51 at a point intermediate the two switch assemblies 36 and 36A.

Also secured to the insulation strip 50 and at the opposite side thereof from the spring arm 52 is a spring strip 54 which is connected to the contact strip 52 at the contact button 55. The contact button 55 is arranged to cooperate with a contact 56 carried by contact spring strip 53.

As shown in Figure 4, there are positioned at opposite sides of the contacts 55 and 56 permanent magnets 57 and 58 held in a bracket 59 affixed at the upper end of the bracket arm 11. The bracket arm 11 thus closes a magnetic circuit between the permanent magnets 57 and 58 at the lower end thereof while at the upper end a magnetic flux flows across the contacts 55 and 56 tending to blow the arc resulting upon opening the contacts outward toward the left as viewed in Figure 3.

The spring arms 44—45, 44A—45A, 46—47, and 46A—47A likewise cooperate respectively in opening and closing several circuits as will be explained. Arc shields 60 are provided to protect the mechanism from arcing at these contacts.

The spring contact arm 52 is operably connected by an extension 61 to the plunger rod 24, so that downward movement of the rod 24 will tend to close contacts 55—56 and the upward movement of rod 24 as upon the unlatching thereof will open the contacts 55—56.

Affixed to the spring arm 54 is a U-shaped member 65 operably connected to spring contact arm 44 and 44A by insulated connectors 66, while the arms 44 and 44A are similarly connected to spring contact arm 46 and 46A respectively by insulated connectors 67.

It will be seen then that upon downward movement of the push rod 24 to a latched position the main switch contacts 55 and 56 will be closed as will the spring switch arms 44—45, 44A—45A, 46—47, and 46A—47A. However upon the electromagnet 10 becoming energized and drawing the armature 15 toward it in a counter-clockwise

direction the stud 35 will draw the latch member 21 from the step 23, so as to release push rod 24. The upward movement of the rod 24 under the biasing force of the spring 28 will then cause switch arm 52 to open contacts 55—56 and switch arms 44, 44A, 46 and 46A to open their respective contacts.

In order to compensate for changes in the resistance of the electromagnet 10 due to variations in temperature there is provided a resistance 70 having a small temperature coefficient of resistance, preferably wound of nichrome wire. The resistor 70 is mounted on the supporting member 13 and is connected in series with the electromagnetic winding 10, the resistance of which is relatively small compared to that of the resistance 70 so that any change in the relative resistance of winding 10 due to temperature effects the total resistance by a negligible amount.

Moreover in order to introduce an immediately acting time delay (of short duration) in the response of the electromagnetic winding 10 to change in an energizing current, there are provided short circuited copper rings 71 which are arranged concentric with the winding of the electromagnet 10. The copper rings 71 tend during change in the energizing current of the electromagnet 10 to generate a magnetic flux retarding the build-up of a sufficient magnetic flux by the electromagnet 10 to actuate the armature 15, thus providing sufficient time lag to prevent tripping of the latch 21 by surge voltages.

The electromagnet 10 and the several switch contacts controlled thereby are connected by conductors 72 leading through a suitable insulation cement 73 provided in the base of the supporting member 13 as shown in Figure 5. The conductors 72 are in turn connected by conductors to suitable external terminals 74 mounted in the base member 13A, as shown in Figures 1 and 5.

The purpose of the overvoltage protector device, heretofore described and claimed in the parent application Serial No. 779,992, filed October 15, 1947, is to prevent damage to an airplane's electrical equipment when malfunctioning of a generating system causes excessively high voltage. The protector device is arranged to open the field circuit of the malfunctioning generator and in addition to effect the disconnection of its control equipment from the generator and to disconnect the generator from the main line without affecting other generating systems connected in parallel to the line. Each of said generating systems is provided with a like protector device.

A typical system according to the invention in which the protector device 32 may be used is illustrated in Figure 6 and may include a generator 80 having a field winding 81 and an inter-pole compensating winding 82. Output line 83 of the generator 80 is grounded, while output line 84 may be connected to a main bus line 85 through a line switch 86 operated by a solenoid 87.

The control equipment for the generator is indicated generally by the numeral 90 and may be of a type described and claimed in the copending application Serial No. 621,515, filed October 10, 1945, by William R. Holmes.

The control equipment 90 includes a variable resistance carbon pile 91 connected in series with the generator field 81 through a conductor 92. The field 81 is connected through conductor 93 to output line 83 and the opposite end of the carbon pile 91 may be connected to the output

line 84 through a conductor 94 and the main switch contacts 55 and 56 of the protector device 32.

The variable resistance carbon pile 91 may be controlled by an adjustable armature 95 shown schematically in Figure 6 and which may be of a type described and claimed in U. S. Patent No. 2,427,805, granted September 23, 1947, in the name of William G. Neild and assigned to Bendix Aviation Corporation.

The armature 95 may be controlled by an electromagnetic winding 96 which may be connected across the generator output lines 83 and 84 by grounded conductor 97 and conductor 98. The conductor 98 may be connected to line 84 through switch members 44-45 of the protector device 32.

Connected across the interpole compensating winding 82 by a conductor 99 and grounded conductor 99A is a potentiometer 100 having a center tap 100A connected to a compensating winding 101 for affecting the carbon pile 91 so as to maintain a predetermined division of load between the several parallel connected generators as is explained in the aforesaid copending application Serial No. 621,515.

The opposite end of the compensating winding 101 may be connected to an equalizer line 102 through a conductor 103, relay switch 104, and switch members 44A and 45A of the protector device 32. The relay switch 104 is controlled by an electromagnetic winding 105 connected across the output lines 83-84 by grounded conductor 106 including resistance 106A, conductor 98 and switch contacts 44 and 45 of protector 32.

The relay winding 105 is controlled by a pilot switch 107 biased by spring tension to the position shown so as to close switch contact 108. Switch 107 is connected to conductor 98 while contact 108 is connected to conductor 106 so that upon switch 107 closing contact 108, relay winding 105 is shunted out of operation.

The pilot switch 107 is controlled by an electromagnetic winding 109 connected through conductor 98 and switch contacts 44-45 of the protector device to output line 84 and through grounded conductor 110 to output line 83.

Upon the output generator voltage rising above a predetermined value the relay switch arm 107 is biased by relay 109 so as to open contact 108 and close a contact 111. The latter action opens the shunt circuit of relay winding 105 causing the winding 105 to close switch 104 whereupon the compensating winding 101 is connected into operation and to the equalizer line 102.

Moreover upon relay switch 107 closing contact 111 a current winding 112 is connected across the open line switch 86 by a conductive passage leading from line 84 through switch contacts 44-45 of the protective device 32, conductor 98, switch 107, contact 111, current winding 112, and a conductor 113 to the main bus line 85. The winding 112 is wound about a permanent magnet 114 and is arranged to cooperate therewith so that upon a current flow from the generator 80 to the main bus line 85 the magnetic effect of coil 112 and permanent magnet 114 will exert an additive effect biasing a relay switch 115 to close contact 116.

The relay switch 115 is connected by a conductor 117 to conductor 94 and through switch contacts 55 and 56 to the output line 84. The contact 116 is connected by conductor 118 through the switch contacts 46-47 of the pro-

tector device 32 to the line relay 87. The closing of switch 115 will then cause energization of the line relay 87 and the closing of the line switch 86 which will shunt differential current winding 112 out of operation.

Cooperating with the winding 112 is a second current winding 120 connected across the interpole compensating winding 82 through conductor 121 and grounded conductor 122. So long as the current flow is from the generator 80 to the main line 85 the winding 120 will exert an additive effect with the permanent magnet 114 tending to hold the control switch 115 closed. However in the event the output of the generator 80 decreases to such a point that the current output of the generator is below that of the main bus line 85, then the winding 120 will exert a differential effect with the permanent magnet 114 tending to decrease the magnetic effect acting on the relay switch 115 so that the switch 115 under spring force is biased to a position opening contact 116. The latter action deenergizes the winding 87 causing line switch 86 to open.

As shown schematically in Figure 6 and specifically in Figures 2-5 switch contacts 46-47, 44-45, 55-56, 44A-45A, and 46A-47A may be closed by manually actuating the push rod 24. The same may be latched in the latter position through action of the latch mechanism 21 as heretofore explained.

The closing of switch contacts 46A-47A connects a sensing coil, the electromagnetic winding 10, across the field 81 of the generator 80 through conductors 130 and 131.

When the voltage across the field 81 reaches a predetermined excessive value for any reason, the sensing coil 10 actuates the armature 15 and through the studs 35 the latch 21, thus releasing the reset rod 24 and opening the main contacts 55-56, and the four pairs of auxiliary contacts 46-47, 44-45, 44A-45A, and 46A-47A.

In the latter event the following action takes effect. The contacts 46-47 open the potential circuit for the line relay 87 and thereby cause line switch 86 to open and effect deenergization of current winding 120. The contacts 44-45 open the potential circuits for the carbon pile voltage coil 96, relay voltage coil 105, and relay voltage coil 109. Deenergization of coil 109 causes in turn relay switch 107 to open contact 111 and thereby the circuit to differential current coil 112. The main contacts 55-56 open the generator field circuit. The auxiliary contacts 44A and 45A open the circuit of the compensating winding 101. The auxiliary contacts 46A and 47A open the circuit of the sensing coil 10.

As an alternative arrangement the switch 44A-45A may be normally open so that upon the latch 21 releasing the reset rod 24 the switch 44A-45A may close a circuit to energize a warning device such as an electric light or bell to indicate that the overvoltage protector has disconnected one generating system from the main bus.

As shown diagrammatically in Figure 6 and claimed in copending application Serial No. 119,724, filed October 5, 1949, a plurality of generators 80, 80A, 80B and 80C may be parallel connected to the main bus line 85. Each of the generators 80A, 80B and 80C has similar control equipment to that indicated generally by numeral 90 and indicated herein as 90A, 90B and 90C, respectively. Likewise the generators 80A, 80B and 80C have protector devices similar to the protector device 32 of the generator 80 and indicated herein as 32A, 32B and 32C, respectively.

Surge voltages due for example to a faulted generator will not actuate the overvoltage protector of the other non-faulted generators. This condition is achieved by the incorporation of the copper washers 71, which act as shorted turns on the sensing coil 10. Such shorted turns in an inductive system generate flux that opposes the flux generated by the coil 10. Thus during change in the energizing current of the coil 10 this opposition retards the build-up of sufficient coil flux to actuate the armature 15, so as to provide a sufficient time lag to prevent tripping of the latch 21 by surge voltages. This time lag is further insured by the construction of the armature 15 and latch 21. The armature 15 has studs 35 arranged to trip the latch 21 after the armature has traveled about two-thirds of its distance to the electromagnet 10. This construction also permits the tripping voltage to be unaffected by friction.

Once the overvoltage protector has operated the reset rod 24 may be pushed down to reset the mechanism by manually compressing the bellows 34.

The overvoltage protector is sealed within the casing 32 so as to protect the same from moisture, dirt and atmosphere.

Although only one embodiment of the invention has been illustrated and described, various changes in the form and relative arrangements of the parts may be made to suit requirements.

What is claimed is:

1. An overvoltage protector for a generator having a field circuit for controlling the output thereof, comprising a main control switch for connecting said generator to said output, a main electromagnetic winding circuit for controlling said main switch, a regulator connected in said field circuit, a control winding for said regulator and adapted to be connected across the output of the generator, an overvoltage protective relay means including a third electromagnetic winding adapted to be connected across the field circuit, a plurality of switch elements operated as a unit by said third electromagnetic winding, said switch elements being arranged to open said main winding circuit, said field circuit, said control winding circuit, said main electromagnetic winding circuit, and said third electromagnetic winding circuit, and a short circuited turn about said third electromagnetic winding and so arranged as to retard operation of said switch elements upon a

transitory voltage surge affecting said third winding.

2. An overvoltage protector for a generator having a field circuit for controlling the output thereof comprising a main control switch for connecting said generator to said output, a main electromagnetic winding circuit for controlling said main switch, a regulator connected in said field circuit, a control winding for said regulator and connectable across the output of the generator, an overvoltage protective relay means including a third electromagnetic winding connectable across the field circuit, a plurality of switch elements, lost motion latch means operably connecting said switch elements and said third electromagnetic winding; said switch elements being arranged to open said main winding circuit, said field circuit, said control winding circuit, said main electromagnetic winding circuit, and said third electromagnetic winding circuit, and a short circuited turn about said third electromagnetic winding and so arranged as to retard operation of said switch elements upon a transitory voltage surge affecting said third winding.

3. An overvoltage protector for a generator having a field circuit for controlling the output thereof comprising a main control switch for connecting said generator to said output, a main electromagnetic winding circuit for controlling said main switch, a regulator connected in said field circuit, a control winding for said regulator and adapted to be connected across the output of the generator, an overvoltage protective relay means including a third electromagnetic winding adapted to be connected across the field circuit, a plurality of switch elements, lost motion latch means operably connecting said switch elements and said third electromagnetic winding; said switch elements being arranged to open said main winding circuit, said field circuit, said control winding circuit, said main electromagnetic winding circuit, and said third electromagnetic winding circuit, and a short circuited turn about said third electromagnetic winding and so arranged as to retard operation of said switch elements upon a transitory voltage surge affecting said third winding, and manually operable means for actuating said switch elements to a closed position.

ROBERT L. BROWN.
